Ezra Ripley of Troy, N.Y.

Assignor to

Nicholas G. Vedder of same place

Letters Patent No 491 Dated Aug 31st 1852.

The schedule referred to in these Letters Patent and making part of the same

To all whom it may concern:

Be it known that I, Ezra Ripley, of Troy, in the County of Rensselaer and State of New York, have invented or produced a new and original design of parlor stove, which I call the "Rosenth Parlor" and do hereby declare that the following is a full, clear, & exact description of the same, reference being had to the annexed perspective drawing making a part of this specification.

The ornamental design of my stove consists of the scrolls (a a a) the scallops (b b) the diamond work (c c) &c. arranged on the top plate A, the scrolls (d d) the ornaments (e e e) the center ornament (f) together with the ornaments (g g g) and (h) arranged and disposed on the front plate B, the end plate C, is ornamented with the figures (i) and (j) and the ornament (k). The bottom plate D, is ornamented with the rosettes (m) and (n) the stars (o o) & corner ornaments (p p) disposed on the mouldings and hearth. E, is the damper; F, is the leg ornamented with the scrolls (g g) and leaf (r).

Having thus described my design of parlor stove, what I claim as new & desire to secure by Letters Patent, is, the ornamental design & configuration of stone plates, the same as herein described & represented in the annexed drawing.
